UNITED STATES PATENT OFFICE.

JAMES W. DREW, OF BRACKETTVILLE, TEXAS.

VEHICLE.

1,081,372.

Specification of Letters Patent. Patented Dec. 16, 1913.

Application filed June 29, 1911. Serial No. 636,073.

To all whom it may concern:

Be it known that I, JAMES W. DREW, citizen of the United States, residing at Brackettville, in the county of Kinney and State of Texas, have invented certain new and useful Improvements in Vehicles, of which the following is a specification.

This invention relates to improvements in wheel-vehicle structures, and more particularly to vehicles employed for farm, road, country or city vehicles.

The objects of the improvements are first, to combine light weight, strength, durability, ease of propulsion and steering with independent pivot axles and a twin-reach gearing system; obviating and eliminating the unpleasant jerking and shaking of the team, driver and passengers caused by the ungovernable front wheels of the common vehicle which gives way when encountering obstructions that are more or less lying in the way. Second, to obviate the weak, dangerous, and much dreaded tendency of the common vehicle to upset when turning from a side hill position to go up the hill, as hereafter explained. I attain these objects by the mechanism illustrated in the accompanying drawing, forming a part of this specification, in which—

Figure 1 represents a plan view of my invention with the wheels and the head portion of the bolster removed. Fig. 2 is a front elevation of one of the members of the two-part "roller" device. Fig. 3 is a perspective view of one of the coupling devices between the reach and the lower bolster members. Fig. 4 is a plan view enlarged of one of the bolsters together with the swiveled axles attached. Fig. 5 is a front elevation of the parts shown in Fig. 4, except the swiveled axles. Fig. 6 is an end view of the two part T bolster detached.

Corresponding and like parts are referred to in the following description and indicated in all the views of the accompanying drawing by the same reference characters.

The improved device embraces in general a supporting frame comprising two two-part bolster devices located where the ordinary axles of an ordinary vehicle are located, the forward bolster device having short swiveled axles at its ends adapted to carry bearing wheels and the rear bolster carrying similar swiveled axles likewise adapted to support bearing wheels. The forward and rear bolster devices are substantially alike and the description of one will

suffice for both. The bolster devices each comprises a lower member 10 and an upper member 11, bolted or otherwise suitably secured together. Each lower bolster member 60 is provided near one end with a recess 12 in which a bearing member 13 is supported, one of the bearing members being shown in perspective in Fig. 3 and is formed with recesses in its ends to engage against the sides 65 of the bolster member 10 and with a central recess to receive a stationary reach-member 14. The reach-member 14 is bolted as represented at 15 to the bearing member 13, and thus rigidly couples the two bolster devices 70 at one side of the center of the running gear, as shown in Fig. 1. Formed in each of the bolster-members 10 near the other end is a recess 16 somewhat longer than the recess 12 and in which a bearing member 17 is mounted 75 for a slight endwise movement, the member 17 being substantially the same as the member 13, as shown in Fig. 1. A movable reach-member 18 extends through the intermediate recess of the bearing members 17 80 and is pivotally united therein by bolts 19. The intermediate recesses of the bearing members 17 are slightly wider than the reach so that the necessary play or movement is permitted when the reach-member 18 85 is actuated as hereafter explained.

The bolster-members 10 are coupled by diagonal braces 20, and connected at 21 to the reach-member 14 is a fulcrum bar 22 which extends over the reach-member 18 and is connected thereto by a pivot bolt 23. The fulcrum member 22 is bolted at 24 to the braces 20 at their crossing points. By this means the fulcrum 22 is rigidly supported in position and serves as a central support for 90 the reach-member 18 so that when the former is actuated it is caused to swing upon the pivot 23. By this means when the forward end of the reach-member 18 is moved away from the stationary reach-member 14 95 the latter will be moved toward the rear end of the reach-member 14, and this movement reversed when the forward end of the reach-member 18 is moved toward the stationary reach-member 14, as will be obvious. The 100 members 17 are thus caused to slide within the recesses in the bolster members 10 and are retained in position by the recesses at their ends which bear upon opposite sides of the lower bolster member.

At its forward end the stationary reach-member 14 is provided with a strap 25

which extends over the upper and lower faces of the reach and forms a bearing for a collar-like device 26, the collar having preferably square flanges 27 at its ends and bearing upon the opposite side faces of the straps. A strap 28 which is substantially a duplicate of the strap 25 is connected to the opposite faces of the movable reach member 18 and forms a bearing for a collar 29 having bearing flanges 30 and is a substantial duplicate of the collar member 26 with its flanges 27.

Extending inwardly from the collar 26 is a half roller member 31, while a similar half roller member 32 extends inwardly from the collar 29. The members 31-32 bear against each other face to face their whole length as shown in Fig. 1. At its center the half roller member 31 is enlarged as shown at 33 with a transverse mortised opening formed through the enlargement, while a similar enlargement 34 is formed upon the roller member 32 and is provided with a similar mortise, the two mortises designed to receive the inner end of the tongue represented at 35. A pivot pin 36 extends through the enlargement 33 and its mortise and likewise through the tongue 35, while a similar pin 37 extends through the enlargement 34 and likewise through the tongue 35. By this means the tongue is coupled to the roller members and when the tongue is moved laterally by the team the roller members will be shifted longitudinally as will be obvious. The collar 26 is provided with a transverse aperture indicated at 38 and designed to receive the outer end of the collar member 32, while a similar aperture 39 is formed in the collar 29 to receive the outer end of the roller member 31. The roller members are thus guided in their movement when the tongue is moved laterally for "cramping" the vehicle. This movement of the tongue it will be obvious causes the movable reach-member 18 to swing upon its pivot 23, the object to be hereafter more fully explained. A swiveled axle is connected to each end of each of the bolster members 10, one for each of the bearing wheels, and as these axle devices are precisely alike, the description of one will suffice for all. The swiveled axles are represented at 40 and are formed with an enlargement 41 at the inner ends extending vertically, each enlargement being provided with an arm 42 at its ends which bear upon the upper and lower faces of the bolster member 10, and extending downwardly through the bolster members 10 and 11 and the arms 42 is a pivot bolt 43. By this means the axles are mounted to swing laterally upon the bolsters and firmly supported relative thereto.

Each of the upper head members 41 is provided with a lateral projection 64, and

coupling the members 64 of the rearward axles is a rod 65, while a similar rod 66 couples the projections 64 of the forward pivoted axles. Connected to the projection 64 next to the movable reach member 18 is a rod 67, while a similar shorter rod 68 is connected to the arm 64 of the forward swivel axle next to the movable reach-member 18. The rods 67-68 are pivotally united at their inner ends, as shown at 69-70 to the movable reach-member 18. By this arrangement it will be obvious that as the reach-member 18 is moved upon its pivot 23, as before described, the pivot axles will be swung correspondingly to cause the wheels 75 to "cramp" as will be obvious.

What I claim as new is:—

1. In a vehicle, a supporting frame including forward and rearward bolsters each having a longitudinally extending recess, a bearing member slidable in each of said recesses, an axle mounted to swing upon each end of each bolster, a reach member mounted to swing intermediate the ends upon said frame and engaging in said bearing members, connecting means between said reach member and said axles, and a draft tongue mounted to swing relative to said frame and connected to said reach member, whereby the axles are simultaneously cramped by the lateral movements of the tongue.

2. In a vehicle of the class described, a supporting frame, pivoted axles turning on said frame and adapted to carry bearing wheels, a reach rigidly connected with said frame, another reach movably supported on said frame, connecting means between the movable reach and the pivoted axles, and roller bearing members 31 and 32 arranged side by side and operating to vibrate the 105 movable reach and simultaneously cramp the wheels, and a draft tongue pivotally connected with both said bearing members, as shown and described.

3. In a vehicle of the class described, a supporting frame, pivoted axles turning upon said frame and adapted to carry bearing wheels, a stationary reach supported upon said frame, a movable reach supported upon said frame, said reaches having bearings at their forward ends, connecting means between said movable reach and said pivoted axles, a half roller member connected to said stationary reach and slidably through the bearing of the movable reach, 120 another half roller member connected to the movable reach and slidably through the bearing of the stationary reach, and a draft tongue pivotally connected to both of said roller members and operating to vibrate the 125 movable reach and effect the simultaneous cramping of said wheels.

4. In a vehicle of the class described, a forward bolster and a rearward bolster, pivoted axles swingingly connected respectively 130

to said bolsters and each adapted to carry a bearing wheel, a reach rigidly connected to said bolsters, a transverse member extending from said rigid reach, a movable reach 5 pivotally supported intermediate the ends and extending loosely through said bolsters, means for coupling said movable reach to said pivoted axles, and a draft tongue connected to said movable reach and operating 10 to effect the cramping of the wheels simultaneously with the lateral movement of the tongue.

5. In a vehicle of the class described, a forward bolster and a rearward bolster, a 15 stationary reach connected to said bolsters, a movable reach pivotally supported intermediate its ends from said stationary reach and extending through said bolsters, a pivoted axle connected to turn upon each end 20 of each of said bolsters and each adapted to carry a bearing wheel, means for coupling said movable reach to said pivoted axles, and a draft tongue connected to said movable reach and operating to effect the cramping 25 of the wheels simultaneously with the lateral movement of the tongue.

6. In a vehicle of the class described, forward and rearward bolsters, each comprising an upper and lower member with recesses in the lower members which are closed by the upper members, pivoted axles adapted to carry bearing wheels and mounted for oscillation on said bolsters, bearing members in said bolster recesses, one bearing 35 member of each bolster being slidable and the other bearing member being stationary, a stationary reach extending through the stationary bearing members, a movable reach extending through the 40 slidable bearing members, means for swingingly connecting said movable reach to said stationary reach, means for coupling said

movable reach to said pivoted axles, a half roller member mounted for oscillation upon said stationary reach, another half roller 45 member mounted for oscillation upon said movable reach, and a draft tongue pivotally connected to both of said roller members.

7. In a vehicle of the class described a supporting frame, pivoted axles turning 50 upon said frame and adapted to carry bearing wheels, a reach member rigidly connected to said frame and extending in advance of the same, a reach member movably supported upon said frame and extending in 55 advance of the same, connecting means between said movable reach member and said pivoted axles, a half roller member connected to said rigid reach and slidable relative to the movable reach, another half roller 60 member connected to said movable reach and slidable relative to the rigid reach, and a draft tongue pivotally connected to both of said roller members and operating to vibrate the movable reach and simultaneously cramp 65 said wheels.

8. In a vehicle of the class described, a supporting frame including bolsters at the front and rear, said bolsters each having their upper portions overhanging the lower 70 portions, axles pivoted to swing beneath the overhanging portions of the bolsters, said axles having oil ducts communicating through their upper faces and covered and protected by the overhanging portions of 75 the bolster when in normal operative position and exposed when the axles are moved into abnormal or inoperative position.

In testimony whereof, I affix my signature in presence of two witnesses.
